UNITED STATES PATENT OFFICE

WILLIAM B. THOMPSON, OF SOUTH MILWAUKEE, WISCONSIN, ASSIGNOR TO BUCYRUS-ERIE COMPANY, OF SOUTH MILWAUKEE, WISCONSIN, A CORPORATION OF DELAWARE

RAIL CLAMP

Application filed April 14, 1928. Serial No. 270,022.

This invention relates to improvements in rail clamps used in connection with railroad cars, excavating machines and the like, which rest upon and travel along railroad rails, and in particular, is an improvement upon U. S. Patent No. 1,222,193, to Pierpont E. Dutcher, granted April 10, 1917.

Heretofore many different kinds of clamps have been used to prevent the movement of the excavating or other machinery along the rails at times when such movement is undesirable, as for instance when the excavator is digging. As such machinery is generally very heavy and great forces tending to move the machinery along the rails are put into action, it is necessary that such a clamp shall be very strong, and that it shall maintain a positive grip upon the rail under the heaviest stress that is at all likely to be put upon it.

My invention is designed to provide a clamp which will be rigidly and firmly held in position on the rail, wherein the clamping part will operate to tighten the clamp in position, and wherein that portion of the clamp which takes the hammer blow or engages the wheel of the truck will rest at all times firmly and solidly on the rail, so that a series of separate impacts will exert no tendency toward releasing the clamp or the clamp locking mechanism.

The objects of my invention are to provide a clamp which will rigidly and securely attach and hold itself upon the rail, which will take the impact of the car wheel without damage or danger of loosening, and which will not gradually work loose under the effect of a series of separate impacts or blows.

It is a further object of my invention to provide a clamp that, instead of working loose under successive impacts, is so constructed that any increase of pressure of the excavator or other machinery against the clamp will rather cause the clamp to grip the rail more strongly and rigidly than before.

Other objects of my invention will appear from time to time in the specification. The invention is illustrated in the accompanying drawings wherein—

Figure 1 is a side elevation of my rail clamp in operative position on the rail.

Figure 2 is a plan view of the clamp in its operative position, and also showing in dotted lines the position when it is about to be disengaged.

Figure 3 shows a vertical section through the rail, with the clamp in end view, taken along the line 3—3 of Figure 1.

Figure 4 is a vertical section, taken along the line 4—4 of Figure 1.

Figure 5 is a side elevation showing the track, a portion of the car wheel, and the clamp in its operative position, in engagement with the track and wheel.

Throughout the drawings the same numbers indicate the same or similar parts.

11 is a railroad rail, having the usual type of head 12, with the usual sloped under surface 13, on either side. A wheel, adapted to run upon the rail and to support the shovel, car, or railroad truck is shown at 14, Figure 5, engaging the clamp 15 and thereby prevented from rolling further to the right.

The body of the clamp 15 is adapted to overlie and be substantially parallel with the head 12 of the rail. The forward portion 16 is adapted to rest smoothly, squarely and firmly upon the rail. A rib or web 17 projects upward from the body of the clamp, and is apertured as at 18, to allow of the insertion of the hand to manipulate the clamp. The upper and outer portions of the rib end in a reinforcement, as shown at 19, the forward surface of which, at 20, is shaped so as to be substantially concentric with the periphery of the car wheel which is to abut it.

A short lug 21 projects to one side of the body of the clamp at the end adjacent the car wheel. This lug extends downward on one side of the rail a short distance, said distance being enough to provide a good grip on the side of the rail, while still allowing that the clamp may, when free, be tipped up to bring this lug out of engagement with the side of the rail, thereby permitting the clamp to be rotated in to the position shown in Figure 2 in dotted lines, in which position this lug 21 is on the other side of the rail head.

Adjacent the front end of the clamp is a

heavy hook, 22, which extends downward and around the head of the rail, and is provided with an inclined rail head engaging surface 23. The inclination of this surface on the upper side of the hook is substantially equal to the inclination of the lower side of the rail head, so that normally this surface rests smoothly and firmly against the lower side of rail head when the parts are in the clamping position. Another heavy hook 24 projects from the same side of the clamp body as the short lug 21. This hook 24 is nearer to the rear end of the clamp than the lug 22. Its upper surface, which is adapted to contact with the lower side of the rail head, is more inclined than the under side of the rail head, so that when the parts are in the position shown in Figure 3, the upper inclined surface of this hook will engage the lower side of the rail head only at the point indicated as 25.

The hooks 22, 24 extend inwardly toward the web of the rail, so that they are both of them in a normal position beneath the head of the rail; the relative size of the parts, however, being such that, when the clamp is rotated into the position shown in dotted lines in Figure 2, there is sufficient gap between the hooks that the clamp may be disengaged from the rail without the hooks engaging the head thereof. To facilitate this, a portion of each of the hooks 22 and 24 adjacent the other of said hooks is cut away, as shown at 26 and 27 on said lugs respectively.

At the rear end, the clamp terminates in a downwardly depending lug 28. Forward of this lug 28, the under surface of the body of the clamp is inclined forwardly and downwardly, as shown at 29. The space thus left between the inclined surface 29 and the rail head 12 is adapted to engage and guide a round tapered pin 30. Normally this pin is confined between the rail head 12, the inclined surface 29, and the lug 28. When the small end of the pin is inserted in this space, and the pin is driven, the driving tends to rotate the clamp upwardly about the forward end thereof, where it engages the rail, and also tends to draw the clamping lugs 22 and 24 tightly against the under surfaces of the rail head 12, thereby strongly binding the clamp against the head of the rail.

It is obvious that if, under pressure of the wheel 14 upon the forward surface 20 of the clamp, the clamp should move along the rail, such motion would roll the clamp over the pin 30. On account of the inclination of the under surface of the clamp at 29, this will tend to raise the rear end of the clamp, and thereby will still more strongly bind the lugs 22 and 24 to the rail. Such increased clamping action will be practically in direct proportion to the increased thrust on the forward end of the clamp, whether that in-

creased thrust is administered as a steady thrust or as a succession of shocks.

The conical shape of the pin 30 not only facilitates its insertion, but also insures a binding action as the pin rolls, entirely apart from the fact of the inclination of the under surface of the clamp at 29. But, with both a taper on pin 30, and an inclination at 29, the greatest binding effect is produced.

It is obvious that the cross section of pin 30 need not be exactly circular, provided that it be curved. In fact, a slight ellipticity should increase the binding effect.

If, for the specific purpose for which my clamp is to be used, it is desirable that it shall be possible to drag the clamp forward along the rail to a new station of the excavator or other device, and to have the clamp set itself when the wheel next backs against it, this may be accomplished in any practicable manner; as, for instance, by having at each side of the clamp, a flexible member (not shown), of each of which members one end is attached to the clamp and the other can be put into temporary connection with one of the projecting ends of the taper pin. When the clamp is drawn forward, this flexible member will draw the taper pin along with the clamp, and will leave it in such a position that the next backward movement of the wheel will reset the clamp.

It is therefore clear that I have provided a rail clamp that is very strong and durable, and is positive in its grip upon the rail under any stress that can be put upon it, remaining at all times securely locked to the rail, with the end that takes the hammer blow or engages the wheel of the truck resting very securely upon the head of the rail; and furthermore, that I have provided a clamp which, though easily removable, cannot become disengaged under impact or other stress, but rather becomes more tightly locked to the rail the greater the stress imposed upon it becomes.

While I have herein described and illustrated one form of my clamp, I purpose not to be limited to the specific embodiment of my invention herein shown, except to the extent that such limitations may be embodied in the appended claims.

I claim:

1. A rail clamp, comprising: a body portion having its under surface at one end adapted normally to overlie and be parallel to the head of the rail to which it is to be applied; said body portion having, adjacent its other end, an under surface forwardly and downwardly inclined; and means for holding the clamp in place and for forcing the first mentioned end thereof into thoroughly continuous contact with the top of the rail; said means comprising clamping hooks adapted to engage the under side of the rail head; said means also comprising a

conical wedge, adapted to be inserted between the body portion and the rail adjacent that end of the clamp which is remote from the rail contacting end of the body portion.

2. A rail clamp, comprising: a body portion having its under surface at one end adapted normally to overlie and be parallel to the head of the rail to which it is to be applied; said body portion having, adjacent its other end, an under surface forwardly and downwardly inclined; and means for holding the clamp in place and for forcing the first mentioned end thereof into thoroughly continuous contact with the top of the rail; said means comprising clamping hooks adapted to engage the under side of the rail head; said means also comprising a tapered wedge, whose cross sections perpendicular to the direction of taper are curved, said wedge being adapted to be inserted between the body portion and the rail adjacent that end of the clamp which is remote from the rail contacting end of the body portion.

3. A rail clamp, comprising: a body portion having its under surface at one end adapted normally to overlie and be parallel to the head of the rail to which it is to be applied; said body having at its other end a downwardly depending lug, and having adjacent to said lug, an under surface forwardly and downwardly inclined; and means for holding the clamp in place and for forcing the first mentioned end thereof into thoroughly continuous contact with the top of the rail; said means comprising clamping hooks adapted to engage the under side of the rail head; said means also comprising a conical wedge, adapted to be inserted between the body portion and the rail adjacent that end of the clamp which is remote from the rail contacting end of the body portion.

4. As a new article of manufacture, a rail clamp with a portion of its under surface forwardly and downwardly inclined, and a conical wedge for insertion between said inclined surface and the rail.

5. As a new article of manufacture, a rail clamp with a portion of its under surface forwardly and downwardly inclined, a downwardly depending lug rearward of said inclined surface, and a conical wedge for insertion between said inclined surface and the rail.

6. As a new article of manufacture, a rail clamp with a portion of its under surface forwardly and downwardly inclined, and a tapered wedge, whose cross sections perpendicular to the direction of taper are curved, said wedge being for insertion between said inclined surface and the rail.

7. As a new article of manufacture, a rail clamp with a portion of its under surface forwardly and downwardly inclined, a downwardly depending lug rearward of said inclined surface, and a tapered wedge, whose

cross sections perpendicular to the direction of taper are curved, said wedge being for insertion between said inclined surface and the rail.

8. A rail clamp, comprising: a body portion having its under surface at one end adapted normally to overlie and be parallel to the head of the rail to which it is to be applied; said body portion having, adjacent its other end, an under surface forwardly and downwardly inclined; and means for holding the clamp in place and for forcing one end thereof into thoroughly continuous contact with the top of the rail; said means comprising clamping hooks adapted to engage the under side of the rail head; said means also comprising a pin of curved cross section, adapted to be inserted between the body portion and the rail adjacent that end of the clamp which is remote from the rail contacting end of the body portion.

9. A rail clamp, comprising: a body portion having its under surface at one end adapted normally to overlie and be parallel to the head of the rail to which it is to be applied; said body having at its other end a downwardly depending lug, and having adjacent to said lug, an under surface forwardly and downwardly inclined; and means for holding the clamp in place and for forcing one end thereof into thoroughly continuous contact with the top of the rail; said means comprising clamping hooks adapted to engage the under side of the rail head; said means also comprising a pin of curved cross section, adapted to be inserted between the body portion and the rail adjacent that end of the clamp which is remote from the rail contacting end of the body portion.

10. As a new article of manufacture, a rail clamp with a portion of its under surface forwardly and downwardly inclined, and a pin of curved cross section for insertion between said inclined surface and the rail.

11. As a new article of manufacture, a rail clamp with a portion of its under surface forwardly and downwardly inclined, a downwardly depending lug rearward of said inclined surface, and a pin of curved cross section for insertion between said inclined surface and the rail.

In testimony whereof I affix my signature.
WILLIAM B. THOMPSON.
